UNITED STATES PATENT OFFICE.

EARL B. ANGELL, OF TROY, MONTANA.

MEMORANDUM DEVICE.

Application filed July 2, 1926. Serial No. 120,235.

This invention relates to an article of manufacture particularly adapted and intended for use in connection with pages of a book, ledger sheets or the like.

In the handling of numerous accounts (in banks for instance) it is frequently necessary to temporarily attach a memorandum on the ledger sheet or page to give notice to the bookkeeper of some condition or situation peculiar to the particular account or other item of business listed on the page or sheet. According to the usual custom a card is made out and given to the bookkeeper but this card is not always conveniently handy when working on the account and frequently the absence or rather separation of the memorandum from the work results in costly error. Furthermore, it is not convenient nor practical in the majority of cases to hold or attach a memorandum to a page or sheet not only because the clip is likely to catch or snag other sheets of paper, but these clips frequently come loose, or often tear the pages and do not enable the pages of a book to lie completely flat if the book is closed. Accordingly, the invention has primarily in view the provision of a simple, practical and efficient device comprising a memorandum surface and means associated therewith for connecting the same to the page of a book, ledger sheet or card of the type used in banking houses for example, to keep a record of customers' accounts, and similar purposes.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings in which

Figure 1 is a view illustrating the application of the invention.

Figure 2 is a rear view of the device.

Figure 3 is a cross sectional view taken on the line 3—3 of Fig. 1.

Similar reference characters designate corresponding parts throughout the several figures of the drawings.

In the embodiment of the invention shown in the drawings it will be observed that the same includes a sheet 1 of paper or other suitable material adapted to receive a record, and if desired one face of the sheet may be

ruled, as indicated at 2 to provide for conveniently receiving the desired memoranda.

One corner of the sheet 1 is provided with a holding member 3 which may be attached to the sheet 1 as indicated at 4 in such a manner as to provide a pocket 5 for receiving the corner of a page or card in such a way that the memorandum sheet 1 may be conveniently held in position with reference to the page, sheet or card shown in dotted lines in Fig. 1 and designated generally as A. From the drawings it will be apparent that the memorandum sheet 1 having the holding means 3 at one corner thereof may be readily and conspicuously placed on the ledger card of the bookkeeping system of a bank in such a way that if payment is to be stopped on a particular check for a customer, the bookkeeper will be definitely and positively advised of the information, and yet the disadvantages of paper clips and the like are entirely avoided while at the same time a consolidated or united memorandum sheet and holding means is provided.

The present devices may be manufactured in large quantities by stationers or paper manufacturers and can be used as freely as ordinary memorandum sheets and yet have greater utility and more advantages than any similar means heretofore known for this purpose.

The memorandum sheet 1 may be made of any desired weight of flexible material and the same is also true of the holding or pocket forming member 3. In practice it has been found convenient to make both members 1 and 3 of paper of suitable weight, and although they are shown as separate members attached in the manner indicated in the drawings, nevertheless it will be understood that it is within the scope of the invention to make the same integral.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:-

1. As an article of manufacture, a memorandum sheet having a non-metallic attaching piece secured to one corner thereof and forming a pocket whereby said sheet may be

detachably fitted to a posting machine page or the like, said attaching piece being flexible and of sufficient thinness to be adapted for insertion between the rollers of a type-writing machine with said page.

2. A detachable memorandum sheet for bookkeeping pages and the like having a

flexible non-metallic and substantially triangular piece of material secured to one corner thereof at two of its edges and leaving the other edge free to provide a pocket.

In testimony whereof I hereunto affix my signature.

EARL B. ANGELL.
